UNITED STATES PATENT OFFICE

ALPHONSE LIPETZ, OF SARATOGA SPRINGS, NEW YORK

STEAM BOILER

Application filed April 21, 1928. Serial No. 271,666.

This invention relates generally to steam boilers of the locomotive type, and particularly to those of such type as are designed for operation under comparatively high pressures of steam, and its object is to provide a structure of such type, which will utilize the exhaust gases for heating the feed water for the boiler.

There are many well recognized advantages pertaining to the locomotive high pressure boiler, but from the standpoint of economy in fuel consumption, this type of boiler has not been found fully satisfactory, in that the temperature of the gases discharged from the boiler is much higher than in those of the low pressure types. In the present invention, the heat of the discharge gases is made available to heat the water in an economizer, to be used as feed water for the steam generating member of the boiler. The temperature of the discharged gases is brought to a comparatively low point, as in the low pressure boiler, while the boiler still maintains the advantages of the high pressure feature.

The improvement claimed is hereinafter fully set forth.

In the accompanying drawings: Figure 1 is a vertical longitudinal central section through a locomotive boiler, illustrating an embodiment of the invention; Fig. 2, a rear view, in elevation, thereof; Figs. 3, 4, 5, 6 and 7, vertical transverse sections, on the lines, *a a*, *b b*, *c c*, *d d*, and *e e*, respectively, of Fig. 1; Fig. 8, a front view, in elevation, Figs. 2-8 inclusive being on enlarged scales; and, Fig. 9, a partial side view, in elevation.

In the practice of the invention, referring descriptively to the specific embodiment thereof which is herein exemplified, the essential elements of a locomotive boiler in accordance therewith, comprise a fire chamber, indicated as a unit by the reference symbol, *A*; a heating chamber for the gases coming from the fire chamber, indicated by *B*; an economizer for heating the feed water for the boiler by means of the gases coming from the heating chamber, indicated by *C*; and a high pressure steam generator, disposed in the fire chamber and heating cham-

ber, indicated by *D*. The detailed description of the essential elements above stated, which follows, is made with notice that they may be varied as to structural detail, in the discretion of a constructor skilled in the art, without departure from the spirit and operative principle of the invention.

In the instance herein set forth, the fire chamber, *A*, comprises the side and top enclosing walls, 1, and end walls, 2 and 3, which are headers for the generator, as will presently appear, the wall, 2, being provided with an opening, 2*a*; for firing the boiler, and the wall, 3, being provided with an opening, 3*a*, and a grate, 4. The heating chamber, *B*, for receiving the gases coming from the fire chamber, is formed by the walls, 5, and communicates with the fire chamber, through the opening, 3*a*, of the wall, 3, which serves as an end wall for the chamber. The opposite end wall is formed by parts of the generator and economizer, as will presently appear.

The economizer, *C*, is constructed somewhat similarly to the waist of the conventional locomotive type of boiler, and comprises a shell, 6, and sheets, 7 and 8, and the tubes or flues, 9, adapted for the passage through them of the gases discharged from the heating chamber.

The high pressure steam generator, *D*, while not necessarily so, in the present instance, constructed in two parts or sections, one of the parts or sections, *Da*, being disposed in the fire chamber, *A*, and the other, *Db*, in the heating chamber, *B*. The section, *Da*, comprises two headers, 2 and 3, which also, as before stated, serve for the end walls of the fire chamber, two upper drums, 10, 10, and two lower drums, 11, 11, connected to the headers in the usual manner, and a series of water tubes, 12, extending between the upper and lower drums.

The section, *Db*, comprises upper drums, 13, 13, a lower drum, 14, a series of water tubes, 15, extending between the upper and lower drums, and a header, 16, provided with an opening, 16*a*. The drums, 13, 13, and 14, are connected, at one of their ends, to the header, 16, and, at their opposite ends, to the

header, 3, this latter header thereby serving as a common header for both sections of the steam generator. By this construction, the sections of the generator are maintained in communication with each other, to insure an equal pressure in both. The headers are constructed hollow throughout, thereby affording communication between the drums. The header, 16, and the plate, 8, serve as end walls 10 for the heating chamber, B.

10 Superheaters of any desired type may be applied and disposed in the boiler at any of the usual points. In the present instance, a superheater, G, is provided in the smoke box, 17, with its units disposed in certain of the flues, 9, which are enlarged to accommodate them in the usual manner, connections, 18, serving to connect the drums, 13, with the throttle (not shown), and the superheaters.

20 The water from the economizer, which usually will be at a comparatively low pressure, is forced into the high pressure steam generator by means of one or more pumps. In the present embodiment, a pump, 19, is employed, which is in communication with the economizer through a conduit, 20, and with the steam generator through a conduit, 21.

While it is desirable that little or no evaporation shall take place in the economizer, provision is however made to take care of the relatively small amount of steam that may be generated. To this end, a drum, 22, is connected to the economizer by means of members, 23, adapting it to receive the steam that 35 may be generated, and a conduit, 24, conveys the steam to the cab turret, 25, of the locomotive, to be used in auxiliaries, or otherwise, as may be desired.

40 As previously stated, the object of the invention is to more advantageously utilize the excessively high temperature discharged gases of a high pressure locomotive boiler, than has previously been done. This presents a comparatively simple problem, in 45 stationary boilers, but in portable boilers, such as the locomotive boiler for instance, space is all important, and therefore several important factors enter into the present invention. It is obviously desirable that the 50 gases of combustion enter the smoke box at as low a temperature as possible. The tubes, 9, of the economizer, which are open at both ends, communicate, at one of their ends, with the heating chamber, B, through the opening, 16a, and with the smoke box, at their opposite ends.

55 The flues, 9, in effect, lengthen the heating chamber between the fire chamber, A, and the smoke box, thereby affording a better 60 opportunity for absorbing the heat of the discharged gases before they reach the chimney.

65 The economizer is preferably maintained at a comparatively low pressure, say, between one hundred and two hundred pounds, while

the high pressure generator may be, say, between four hundred and five hundred pounds, as an illustration. It is highly desirable that the economizer be maintained at as close a 70 temperature to the saturation temperature as possible, with minimum evaporation of the water therein. To accomplish this, several factors must be considered. Careful consideration must be given to the relative proportioning of the generator and economizer, to 75 insure the proper division of heat between them. The economizer must also be properly positioned relative to the fire chamber, for if it is too near, there will be excessive evaporation. That is to say, the heating chamber, 80 B, should be of sufficient relative size to prevent excessive evaporation of the water in the economizer, while insuring the desired high temperature. By a proper consideration of these features, the water in the economizer may be raised from a certain temperature to approximately the saturation temperature, at moderate pressure, and the water in the generator raised from this temperature 85 to the saturation temperature, at high pressure, and complete evaporation of all the water thereby effected.

90 The attainment of the above conditions may be, at times, more or less disturbed by outside factors entering in, or otherwise, as for instance, by varying the fire ratings. The present invention contemplates the provision of means for correcting this, to a greater or less extent, and is intended to cover this feature broadly, as there are various ways of accomplishing it. For instance, it may be accomplished by varying the pressure in the economizer, between reasonable limits, say one hundred and two hundred pounds; or by controlling the amount of water fed to the economizer; or when a feed water heater is used for the economizer, by varying the amount of exhaust steam led into the feed water heater, thus affecting the temperature of the water entering the economizer from the feed water heater. The variation in the amount of exhaust steam fed may be effected manually, or automatically, by using thermostatic or pressure control, to throttle the exhaust steam inlet to the feed water heater.

100 In the present construction, to better insure the desired high temperature and minimum evaporation of the water in the economizer, a thermostat is employed. To this end, a feed water heater, 26, is provided, communicating with the exhaust passage of the cylinder, 27, through a conduit, 28, to receive steam therefrom, and also communicating with the water tank (not shown) in the usual manner.

110 The feed water heater is further connected with the economizer by a conduit, 29, whereby the heated water from the heater is fed thereto. The conduit, 28, is provided with a control valve, 30, which is suitably connected to a thermostat, 31, to be operated thereby in a 120 125

well known manner. The thermostat is connected to the economizer in a well known manner, whereby it will automatically respond to a change in the temperature of the water in the economizer.

While a direct temperature control has been described by way of illustration, it will be understood that, if desired, the temperature may be controlled by indirect means. For instance, the temperature may be indirectly controlled by the control of the pressure, any suitable or well known device being employed for this purpose. By thus maintaining the pressure control, the temperature will also be controlled.

It will be seen from the foregoing description that the temperature in the economizer may be kept substantially constant, by insuring a proper division of heat between the generator and economizer.

The generator, which comprises three headers, with four drums, and water tubes in the fire chamber, and three drums and water tubes in the heating chamber, with the intermediate header between the two chambers, provides for a very intensive evaporation, due to the large direct heating surface, which is enhanced by feeding the generator under pressure, by means of a pump. This secures a very high capacity in a limited space. Moreover, the scale precipitation takes place in the economizer, and practically no scale is formed in the generator, thus eliminating the difficult operation of cleaning the inside of the water tubes. It will be understood, however, that, if desired, an additional scale precipitating device, of suitable or well known construction, may be installed in the usual manner. Furthermore, the drums of the generator may be provided with the usual plug openings, or man-holes, to facilitate the cleaning of the water tubes of the generator in the usual manner, when found desirable.

The section of the steam generator comprised in the fire chamber is provided with four drums, the lower two of which are located well out at the sides of the chamber. The water tubes connect the upper and lower tubes at each side, and are arranged well out at the respective sides. This permits a large central portion of the chamber unobstructed by the tubes for the combustion of the fuel. In this space an arch, H, is shown, which divides the chamber into upper and lower parts, and directs the hot gases in such a manner that they come in contact with the entire surfaces of the tubes before they reach the heating chamber in front. In this latter chamber there are but three drums employed. Two of these are disposed in the top of the chamber at each side thereof, and the third is centrally located at the bottom. A nest of water tubes connect the upper drums with the lower drum, and are arranged trans-

versely of the chamber to include a width substantially equal to the diameter of the economizer, and the chamber itself is made approximately this width, as clearly shown in Figs. 4 and 5 of the drawings.

The hot gases pass from the fire chamber, through the contracted heating chamber, and finally through the economizer. The water tubes, arranged throughout substantially the entire space of the heating chamber, are in the direct path of these gases, and thus are most effectively heated thereby. This construction and arrangement of the features of the generator presents a desirable embodiment of a form of generator especially adapted to operate under certain conditions and with certain kinds of fuel.

The invention claimed as new and desired to be secured by Letters Patent is:

1. A locomotive boiler comprising a fire chamber; a contracted heating chamber in advance thereof; a steam generator having a section disposed in said fire chamber and a section disposed in said heating chamber and having upper and lower longitudinal drums and rows of substantially vertical, spaced, water tubes extending from top to bottom throughout the entire width of the heating chamber and connected to said drums; and a fire tube economizer forward of the heating chamber for heating feed water for said steam generator.

2. A locomotive boiler comprising a fire chamber; a heating chamber in advance thereof; a sectional steam generator having one of its sections disposed in said fire chamber and having a series of water tubes on each side of the chamber providing a space therebetween for the combustion of fuel, and said generator having another one of its sections in said heating chamber and having upper and lower longitudinal drums and rows of substantially vertical, spaced, water tubes extending from top to bottom throughout the entire width of the heating chamber and connected to said drums; and a fire tube economizer forward of the heating chamber for heating feed water for said steam generator.

3. A locomotive boiler comprising a fire chamber; a contracted heating chamber in advance thereof; a steam generator having a section in the fire chamber and a section in the heating chamber having upper and lower longitudinal drums and rows of substantially vertical, spaced, water tubes extending from top to bottom throughout the entire width of said heating chamber and connected to said drums; and an independent fire tube economizer forward of the heating chamber for heating feed water for the steam generator, said economizer having a diameter substantially equal to the contracted heating chamber.

4. A locomotive boiler comprising an independent fire tube economizer for heating

feed water; a fire chamber; a heating chamber between the fire chamber and the economizer; a high pressure tubular steam generator disposed in said chambers, including 5 water tubes and a set of upper and lower drums in communication with the tubes in one chamber, water tubes and a set of upper and lower drums in communication with said last mentioned water tubes in the other chamber, an end header for each set connecting the drums thereof, and an intermediate header disposed between the chambers connecting all the drums, whereby the water tubes in one chamber are brought into communication 10 with the water tubes in the other chamber; a passage for feeding water from the economizer to the generator; means in said passage for variably controlling the rate of feed water therethrough; a feed water heater for 15 the economizer; and means for feeding the water from the heater to the economizer.

5. A locomotive boiler comprising a fire chamber; a heating chamber forward of the fire chamber; a sectional high pressure tubular steam generator disposed in said chambers, one section of said generator being disposed in the fire chamber and one section of 20 said generator being disposed in the heating chamber and having rows of substantially 25 vertical, spaced, water tubes extending from top to bottom throughout the entire width of the heating chamber; a fire tube economizer in advance of the heating chamber for heating feed water for the steam generator; a hot 30 water feeder for said economizer; means for supplying heat to the feeder; means for controlling the temperature of the feed water 35 responsive to variations in temperature of the water in the economizer; means for supplying water from the feeder to the economizer; and means for supplying water from the 40 economizer to the steam generator.

6. A locomotive boiler comprising a fire chamber; a heating chamber disposed forwardly of the fire chamber; a steam generator disposed in said chambers, having lower 45 water drums, upper drums for the collection of steam and a plurality of tubes connecting the steam and water drums, extending 50 throughout the fire chamber and heating chamber; an independent fire tube economizer for heating feed water for said steam generator; a feed water passage communicating with said steam generator and said 55 economizer; means in said passage for variably controlling the rate of feed of water therethrough; a feed water heater for the economizer; and means for feeding the water from said heater to the economizer at a temperature 60 variable with relation to the temperature of the water in the economizer.

7. A locomotive boiler comprising a fire chamber; a heating chamber disposed forwardly of the fire chamber; an independent 65 fire tube economizer for heating feed water,

disposed forwardly of the heating chamber, and adapted to be heated by gases of combustion from the heating chamber; a steam generator disposed within said chambers throughout the length thereof comprising a 70 lower water drum, an upper drum for the collection of steam, a plurality of tubes connecting the steam and water drums, and a plurality of headers connecting the steam and water drums, one of the headers constituting a rear wall for the fire chamber, and another of the headers constituting a dividing wall between the fire and heating chambers, and having an opening for the passage of gases 75 of combustion from the fire chamber to the heating chamber; a passage communicating with the steam generator and the economizer for feeding water from the economizer to the steam generator; means in said passage for variably controlling the rate of feed of water 80 therethrough; a feed water heater for the economizer; a passage communicating with the economizer and the feed water heater; and means for variably controlling the temperature of water feed through said last mentioned 85 passage.

8. A locomotive boiler comprising a fire chamber; a heating chamber disposed forwardly of the fire chamber; an independent fire tube economizer for heating water, disposed forwardly of the heating chamber, and adapted to be heated by gases of combustion from the heating chamber; a steam generator disposed in said chambers, having a 90 lower drum of water, an upper drum for the 95 collection of steam, and a plurality of tubes connecting the steam and water drums, extending throughout the said fire and heating chambers; a passage communicating with the steam generator and the economizer for feeding water from the economizer to the steam generator; means in said passage for variably 100 controlling the rate of feed of water therethrough; a feed water heater for the economizer; and means for variably controlling the temperature of the feed water for the 105 economizer.

9. A locomotive boiler comprising a fire chamber; a heating chamber disposed forwardly of the fire chamber; an independent fire tube economizer for heating water disposed forwardly of the heating chamber and adapted to be heated by gases of combustion from the heating chamber; a steam generator disposed in said chambers, comprising a lower 115 water drum, an upper drum for the collection of steam, and a plurality of tubes connecting the steam and water drums, extending throughout the said fire and heating chambers; a feed water heater for the economizer; means for feeding the water from the heater to the economizer; means responsive to temperature changes of the water in the economizer operable to effect the temperature of the feed water, for controlling the tempera- 120 125 130

ture of the water in the economizer; a passage communicating with the steam generator and the economizer for feeding water from the economizer to the steam generator; and 5 means in said passage for controlling the rate of flow of feed water therethrough.

10. A locomotive boiler comprising a fire chamber; an independent fire tube economizer for heating feed water; a heating chamber 10 between the fire chamber and the economizer; a steam generator disposed in said chambers including water and steam retaining means and water tubes in each chamber in communication with said means; a feed water heater 15 for said economizer; means for feeding the water from the heater to the economizer; automatic means responsive to temperature changes of the water in the economizer operable to effect the temperature of the feed 20 water for the economizer, for controlling the temperature of the water in the economizer; and means for feeding water from the economizer to the generator.

11. A locomotive boiler comprising a fire 25 chamber; a heating chamber disposed forwardly of the fire chamber; an economizer comprising a shell and fire tubes disposed longitudinally of the shell, said economizer being disposed forwardly of the heating 30 chamber and adapted to be heated by gases of combustion therefrom, for heating feed water; a steam generator disposed in said chambers, comprising two units one disposed in the fire chamber and the other disposed in the heating chamber, each unit comprising a 35 lower water drum, an upper drum for the collection of steam, and a plurality of tubes connecting the steam and water drums, and a header common to both sections, bringing the 40 upper and lower drums thereof into communication; a passage communicating with one of the drums and the economizer for feeding water from the economizer to said drum; means in said passage for variably controlling 45 the rate of flow of said water therethrough; a feed water heater for the economizer; and means for feeding water from the heater to the economizer.

12. A locomotive boiler comprising a fire 50 chamber; an independent fire tube economizer for heating feed water; a heating chamber between the fire chamber and the economizer in communication with the fire tubes of said 55 economizer; a steam generator disposed in said chambers including separate horizontal water and steam retaining drums and water tubes in communication with said drums extending throughout the said chambers; a passage for feeding water from the economizer 60 to the steam generator; means in said passage for variably controlling the rate of feed of water therethrough; a feed water heater for the economizer; and means for feeding water from the heater to the economizer, said economizer being disposed and of a size, relative to 65

the generator to prevent any substantial amount of steam to be formed in the economizer during the normal operation of the locomotive.

13. The combination of a steam generator; 70 a fire tube economizer for heating feed water for said steam generator; a hot water feeder for said economizer; means for supplying heat to the feeder operatively responsive to variations in the temperature of the water in the economizer; means for feeding water from the feeder to the economizer; and means for feeding water from the economizer to the steam generator. 75

14. The combination of a steam generator; 80 a fire tube economizer for heating feed water for said steam generator; a hot water feeder for said economizer; means for supplying heat to the feeder; thermostatic means for controlling the heat supply to the feeder, operatively responsive to variations in the temperature of the water in the economizer; means for feeding water from the feeder to 85 the economizer; and means for feeding water from the economizer to the steam generator. 90

15. In a locomotive boiler, the combination 95 of a steam generator; a fire tube economizer for heating feed water for said steam generator; a hot water feeder for said economizer; means for supplying heat to the feeder operatively responsive to variations in the temperature of the water in the economizer; means for feeding water from the feeder to the economizer; and means for feeding water from the economizer to the steam generator. 100

16. In a locomotive boiler, the combination 105 of a steam generator; a fire tube economizer for heating feed water for said steam generator; a hot water feeder for said economizer; means for supplying heat to the feeder; thermostatic means for controlling the heat supply to the feeder, operatively responsive to variations in the temperature of the water in the economizer; means for feeding water from the the feeder to the economizer; and means for feeding water from the economizer to the steam generator. 110

17. The combination of a steam generator; 115 a fire tube economizer for heating feed water for said steam generator; a hot water feeder for said economizer; means for supplying heat to the feeder operatively responsive to variations of pressure in the economizer; means for feeding water from the feeder to the economizer; and means for feeding water from the economizer to the steam generator. 120

18. In a locomotive boiler, the combination 125 of a steam generator; a fire tube economizer for heating feed water for said steam generator; a hot water feeder for said economizer; means for supplying heat to the feeder operatively responsive to variations of pressure in the economizer; means for feeding water from the feeder to the economizer; and means for 130

feeding water from the economizer to the steam generator.

19. In a locomotive boiler, the combination of a fire chamber; an economizer for heating feed water; a heating chamber between the fire chamber and economizer; a high pressure steam generator disposed in the chambers; a hot water feeder for said economizer; means for supplying heat to the feeder; thermostatic means for controlling the heat supply to the feeder, operatively responsive to a variation in temperature of the water in the economizer; a passage for feeding water from the economizer to the generator; and means in said passage for variably controlling the rate of feed of water therethrough.

20. In a locomotive boiler, the combination of a fire chamber; an economizer for heating feed water; a heating chamber, between the fire chamber and economizer; a high pressure steam generator disposed in the chambers; a hot water feeder for said economizer; means for supplying heat to the feeder; automatic means for controlling the heat supply to the feeder, operatively responsive to a variation in temperature of the water in the economizer; and means for feeding water from the economizer to the generator.
